CLOTHESPIN RACK

Samuel Geller, Brooklyn, N. Y.

Application November 2, 1945, Serial No. 626,206

4 Claims. (Cl. 312—42)

1

This invention relates to a new and useful clothespin rack permitting storage of a large multitude of clothespins within a minimum amount of space and ready removal of any desired number of clothespins from said rack. While not limited thereto this invention relates particularly to the type of clothespin rack which can be hung up or otherwise affixed in one corner of a laundry room forming a neat container for clothes pins.

The new device is extremely simple in structure, very easy to assemble, and very economical in operation. The number of operating parts which could be worn out or may ever need replacement is extremely small. Initial and operating costs of the device are therefore at a minimum permitting every housewife and every laundry to take advantage of this great improvement in efficiency.

Briefly, the new invention comprises a plurality of openings for clothespins, one clothespin above the other and means for retaining these clothespins in said openings permitting withdrawals of one or more clothespins whenever required. In one embodiment of the invention, a simple and efficient locking means for the device of the invention is also envisioned.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the device made in accordance with the invention.

Fig. 2 is a plan top view of the device.

Fig. 3 is a vertical section through the line 3—3 of Fig. 2.

Fig. 4 is the lower fragment of a vertical section through line 4—4 of Fig. 2.

Fig. 5 is a perspective view of an inside fragment of the device shown without the clothespins.

Fig. 6 is a detail showing the spring retaining the clothespins alone.

Fig. 7 is a perspective view illustrating another embodiment of the instant invention.

Fig. 8 is a detail showing the essential part of the embodiment of Fig. 7 in perspective view.

Fig. 9 is a bottom plan view of the device shown in Figs. 7—8.

Fig. 10 is a view similar to Fig. 9 showing another modification of the invention.

Fig. 11 is a fragmentary perspective view showing another form of the invention.

2

In accordance with the invention a container 10 is provided with a cover 10^a hinged at 10^b, and having walls 11 and 12 at right angles to each other and defining a plurality of parallel compartments 13 wide enough to permit insertion of the narrow sides of clothespins 14, yet not wide enough to permit sideways overturning of the clothespins.

In a preferred form of the invention the container 10 is deep enough to permit positioning of a plurality of clothespins 14 one above the other in one and the same compartment 13.

Near the bottom of each compartment 13 a spring 15 extends from a nail 16 in one of the defining walls 11 or 12. This spring 15 is positioned so as to permit protrusion of the prongs 17 of the individual clothespin 14 from the container 10 in graspable position. Spring 15 normally extends in nearly horizontal position from the supporting wall 11 or 12 but can be flexed so as to permit downward passage of the clothespins 14. Attachment loops 18 and bolt 19 to a supporting wall 20 for the container 10 may be provided. This permits positioning of the device in any desired position.

In operation clothespins 14 are inserted with their prongs 17 down into the individual compartments 13 one after the other. They will fall through said compartment until stopped by spring 15 and one clothespin 14 will stay on top of the other resting its prong 17 on the head portion 21 of the preceding clothespin. Whenever desired a clothespin 14 will be grasped by its prongs 17 and removed downwardly from the compartment 13 causing the next clothespin to follow into the space vacated by the removed clothespin.

In the embodiment shown in Figs. 7—9 a horizontal locking device 22 comprising a frame 23 holding a plurality of parallel bars 24 and attached to a hinge 25 on one lower edge of the container is provided. The locking device 22 has a slit hinged handle 26 cooperating with a loop 27 on the lower side of the container. It is, of course, understood that horizontal bars 24 are arranged so as to fit into any protruding prongs 17 of clothespin 14 being arranged in parallel with springs 15.

The operation of this embodiment of the invention is the same as the preceding embodiment. However, it is now possible to lock the device so as to prevent withdrawal of pins when such withdrawal by unauthorized persons is not desired. Any of a multitude of locks can naturally be used to hold slit handle 26 on loop 27.

In Fig. 10 the spring finger 15' is shown to be imbedded in the wall 11.

In Fig. 11 the attachment loops 18' are shown to be secured to the end wall 12. In other respects this form of the invention is similar to the previous form, and corresponding parts are indicated by like reference numerals.

While I have illustrated and described the preferred embodiments of my invention, it is to be understood that I do not limit myself to the 10 precise constructions herein disclosed and the right is reserved to all changes and modifications coming within the scope of the invention as defined in the appended claims.

Having thus described my invention, what I 15 claim as new, and desire to secure by United States Letters Patent is:

1. A clothespin rack comprising in combination a plurality of compartments defined to permit lengthwise vertical passage of clothespins therethrough, and spring members yieldingly restraining downward passage of such clothespins, said spring members being attached to the walls of said individual compartments near the lower end of said compartments and extending substantially horizontally therefrom and means for attaching said rack to a wall, said clothespin rack also including locking means for said clothespins in said rack, said locking means comprising a set of parallel bars in a frame for engaging between the prongs of the lowermost clothespins in said rack.

2. A clothespin rack comprising in combination a plurality of compartments defined to permit lengthwise vertical passage of clothespins therethrough, and spring members yieldingly restraining downward passage of such clothespins, said spring members being attached to the walls of said individual compartments near the lower end of said compartments and extending substantially horizontally therefrom and means for attaching said rack to a wall, said clothespin rack also including locking means for said clothespins in said rack, said locking means comprising a set of parallel bars in a frame for engaging between the prongs of the lowermost clothespins in said rack, said locking means being hinged to one of the walls of said rack.

3. A clothespin rack comprising in combination a plurality of compartments defined to permit lengthwise vertical passage of clothespins therethrough, and spring members yieldingly restraining downward passage of such clothespins,

5 said spring members being attached to the walls of said individual compartments near the lower end of said compartments and extending substantially horizontally therefrom and means for attaching said rack to a wall, said clothespin rack also including locking means for said clothespins in said rack, said locking means comprising a set of parallel bars in a frame for engaging between the prongs of the lowermost clothespins in said rack, said locking means being hinged to one of the walls of said rack and having cooperating means for retaining a conventional lock.

4. A clothespin rack comprising a container having an open bottom and sub-divided internally into a plurality of compartments into which a plurality of clothespins can be engaged one above the other with the prongs thereof extended downward, springs attached to the walls of said compartments to engage between the prongs of the lowermost clothespins to removably support the clothespins in said compartments with the prongs of the lowermost clothespins extending from the open bottom of said container, a rectangular frame extended across the open bottom of said container about the projecting prongs of the lowermost clothespins, said frame being hingedly connected at one end to the bottom of said container to be pivoted between an operative position extended across the open bottom or an inoperative position depended from the bottom of said container, means for releasably locking said frame in its operative position extended across the open bottom of said container, and a plurality of parallel bars extended across said frame to engage between the adjacent faces of the projecting prongs of the lowermost clothespins in the operative position of said frame to retain the clothespins against unauthorized removal from said container.

SAMUEL GELLER.
